UNITED STATES PATENT OFFICE

162,224

COMBINATION COMB AND BRUSH WALL RACK

Lawrence J. Ricard, Brooklyn, N. Y.

Application August 31, 1949, Serial No. 4,777

Term of patent 14 years

(Cl. D4—3)

To all whom it may concern:

Be it known that I, Lawrence J. Ricard, a citizen of the United States, residing in Brooklyn, Kings County, city and State of New York, have invented a new, original, and ornamental Design for a Combination Comb and Brush Wall Rack, of which the following are the specifications.

With reference to the following drawings forming a part hereof, of which:

Fig. 1 is a top plan view of a combination comb and brush wall rack, showing my new design.

Fig. 2 is a front elevational view.

Fig. 3 is a side elevational view, and

Fig. 4 is a perspective view thereof.

What I claim is:

The ornamental design for a combination comb and brush wall rack, substantially as shown.

LAWRENCE J. RICARD.
